HAND AND ARM SUSPENDED BATH AND WASHING SPONGE OR THE LIKE

George Virneburg, New York, N. Y.

Application July 23, 1949, Serial No. 4,101

Term of patent 7 years

(Cl. D9—2)

To all whom it may concern:

Be it known that I, George Virneburg, a citizen of the United States, residing at New York, in the county of New York and State of New York, have invented a new, original, and ornamental Design for a Hand and Arm Suspended Bath and Washing Sponge or the like, of which the following is a specification, reference being had to the accompanying drawing, forming a part thereof.

In the drawing:

Fig. 1 is a front perspective view of a hand and arm suspended bath and washing sponge or the like, showing my new design;

Fig. 2 is a side elevational view thereof; and

Fig. 3 is a rear view thereof.

I claim:

The ornamental design for a hand and arm suspended bath and washing sponge or the like, substantially as shown,

GEORGE VIRNEBURG.
